UNITED STATES PATENT OFFICE.

CHARLES DECKER, OF NEW YORK, N. Y.

IMPROVEMENT IN PASSENGER-REGISTERS.

Specification forming part of Letters Patent No. **152,614**, dated June 30, 1874; application filed May 9, 1874.

To all whom it may concern:

Be it known that I, CHARLES DECKER, of the city, county, and State of New York, have invented a new and Improved Passenger-Register; and I do hereby declare the following to be a full, clear, and exact description thereof, which will enable those skilled in the art to make and use the same, reference being had to the accompanying drawing, forming part of this specification, in which drawing—

Figure 1 represents a face view of my register open. Fig. 2 is a similar view of the half-fare register detached. Fig. 3 is a face view of the register closed. Fig. 4 is a vertical central section of the same.

Similar letters indicate corresponding parts.

This invention relates to an apparatus for registering and announcing to the passengers the number of fares received by the conductor in railroad-cars, &c., without the use of punches or tickets, so as to save material and better enable the conductor to collect the fares.

The improvements are fully hereinafter described and claimed.

In the drawing, the letter A designates the case of my register, which is made in two parts, containing, respectively, the full-fare and half-fare registering devices, the face-plates of which case are provided with holes or apertures, Fig. 3, beneath which the registering figures or characters are successively brought to view, as hereinafter explained. A' designates the portion of the case allotted for registering full fares, and A'' that for registering half-fares. Referring to the full-fare register, B is the adding-wheel, and C the multiplying-wheel, which are mounted on the opposite ends of a shaft or arbor, D, so that they are brought immediately beneath the face-plates above mentioned. Between the two wheels, on the said arbor D, is the bell or gong E. The said wheels B C are provided with teeth or ratchets b, opposite to each of which, on the faces of the wheels, is placed a figure or character, as shown. The adding-wheel B has successive figures, such as 1, 2, 3, 4, &c., while the multiplying-wheel has multiples of the highest number of these figures—that is to say, if, as in the present example, the highest figure of the adding-wheel is 25, that will constitute the lowest figure of the multiplying-

wheel, thence upward, 50, 75, 100, &c. These figures are placed on the outer faces of the wheels, and show on opposite sides of the register-case, a being the aperture of the adding-wheel, and a', Fig. 4, that of the multiplying-wheel. The adding-wheel B is engaged by a pawl, c, which is attached to the stem of a button, F, arranged in the side of the case A, and which is held by a spring, d. When this button F is depressed by the thumb or finger, the register-case being held in the hand by its handle G, the adding-wheel is turned by the pawl c to the extent of one of its teeth, or of one figure, so that a new or higher figure is registered or brought to view beneath the aperture a in the face-plate. The adding-wheel is prevented from turning in the wrong direction by a detent, c'. Thus, if the conductor is required to depress the button F whenever he receives a fare, beginning with the lowest figure, the figure last registered or exposed to view will denote the number of fares he has taken. If he receives more fares than there are figures upon the adding-wheel, the same are registered by the multiplying-wheel, which is actuated in the following manner: Upon the under side of the adding-wheel B is a pin, e, located at any point along the rim of the said wheel, in the path of which is a catch, f, secured to a slide, H, which is arranged and held by a spring, g, in the side of the register-case. This slide H carries a pawl, h, which engages with the teeth or ratchets of the multiplying-wheel c in such a manner that when in rotating the adding-wheel the pin e strikes the catch f, it displaces it, together with the slide H, which, by the pawl, turns the multiplying-wheel to the extent of one of its teeth, or of one figure. The multiplying-wheel is thus turned at every revolution of the adding-wheel, and beginning with the highest figure of the adding-wheel, (which is the lowest figure of the multiplying-wheel,) it is multiplied as many times as the adding-wheel is rotated or revolved. In other words, when the figures of the adding-wheel are exhausted, the highest figure thereof is registered by the multiplying-wheel, or a multiple thereof, and by adding the registered figures of the two wheels together, the result will show the number of fares the conductor has taken. The

act of depressing the button F, so as to register a fare, is announced or signaled to the passenger by a sounding of the gong E, whereby fraud is prevented on the part of the conductor. This is effected by attaching to the stem of the button F an arm, *i*, which is in line with a pawl, *j*, pivoted to the short arm I of the bell-crank lever I J. The long arm J of this bell-crank lever carries the clapper K of the gong or bell, and it is pivoted in the register-case at *k*.

When the button F is depressed, as above mentioned, the arm *i* is thrust forward until it strikes the pawl *j*, whereby this, together with the bell-crank lever, is displaced, so as to cause the clapper to strike the bell. A spring, *l*, in contact with the long arm J of the bell-crank lever, has a tendency to throw it, with the clapper K, upon the bell, and by this means a sounding of the same is insured. The pawl *j*, which is engaged by the arm *i* in depressing the button, is pivoted at or near the end of the short arm I of the bell-crank lever, and it is provided with a stop, *m*, abutting against the edge thereof in such a manner that the pawl will yield to a backward movement of the arm *i*, so as to allow the same to pass over it, while it is held or prevented from giving way when such arm is moved forward in depressing the button.

As hereinbefore mentioned, to enable the conductor to register half-fares, I have combined with the wheels B C a secondary or auxiliary adding and multiplying wheel, L M, Fig. 2. These wheels are placed in the front portion of the register-case. *t* designates the aperture of the auxiliary adding-wheel, and *u* that of the auxiliary multiplying-wheel. The said auxiliary wheel L M is acted upon in like manner to the wheels B C by a button, N, the shank O of which is slotted and guided upon

a pin, *n*. This button carries a pawl, *p*, which engages with the ratchets of the adding-wheel L, and on the face of this wheel is a pin, *q*, engaging with a ratchet-wheel, P, which is mounted on the arbor of the multiplying-wheel. The pin *q* serves to turn the ratchet-wheel P, and with it the multiplying-wheel, to the extent of one figure once to every revolution of the adding-wheel, so as to multiply the number of fares in like manner described with reference to wheels B and C. The wheel L is held by a detent, *r*, and the wheel P by a detent, *s*, so as to prevent their turning automatically, or in the wrong direction. Upon the shank of the button N is an arm, V, which is bent in line with a secondary pawl, *w*, Fig. 1, pivoted similarly to the pawl *j* upon the short arm *i* of the bell-crank lever. This pawl *w* is braced or held by a spring, *x*, affixed upon the bell-crank lever.

When the conductor wishes to register a half-fare he depresses the button N, whereby the adding-wheel L, Fig. 2, is turned to the extent of one figure, while at the same time the bell-crank lever is moved or oscillated through the bent arm *r*, so as to sound the bell.

What I claim as new, and desire to secure by Letters Patent, is—

The combination of the adding and multiplying wheels B C with the slide H, having the catch *f*, pawl *h*, and reacting spring *g*, all constructed to operate substantially as described.

This specification signed by me this 27th day of March, 1874.
